DESIGN FOR AN ASH TRAY

Andrew L. Henkel and Burke M. Ewing, Chicago, Ill., assignors to The Brunswick-Balke-Collender Company, Chicago, Ill., a corporation of Delaware

Application April 10, 1940, Serial No. 91,578

Term of patent 14 years

To all whom it may concern:

Be it known that we, Andrew L. Henkel and Burke M. Ewing, both citizens of the United States and both residing in the city of Chicago, in the county of Cook, State of Illinois, have jointly invented a new, original, and ornamental Design for an Ash Tray, of which the following is a specification, reference being had to the accompanying drawing, forming a part thereof.

Figure 1 is a top plan view of an ash tray embodying our design;

Figure 2 is a front elevational view thereof;
Figure 3 is an end elevational view thereof, looking at the lefthand end of Figure 1.

We claim:

The ornamental design for an ash tray, as shown.

ANDREW L. HENKEL.
